MAntonelli, PLLC.

(57) **CLAIM**

The ornamental design for a gun stock, as shown and described.

DESCRIPTION

FIG. 1 is a perspective view of a gun stock in accordance with my new design;

FIG. 2 is a front left bottom perspective view of the gun stock of FIG. 1;

FIG. 3 is a front view of the gun stock of FIG. 1;

FIG. 4 is a rear view of the gun stock of FIG. 1;

FIG. 5 is left side view of the gun stock of FIG. 1;

FIG. 6 is a right side view of the gun stock of FIG. 1;

FIG. 7 is a top view of the gun stock of FIG. 1;

FIG. 8 is a bottom view of the gun stock of FIG. 1;

FIG. 9 is a front left bottom perspective view of the gun stock of FIG. 1 with an illustrative removable accessory stored in the gun stock;

FIG. 10 is a perspective view of another embodiment of a gun stock in accordance with my new design;

FIG. 11 is a front left bottom perspective view of the gun stock of FIG. 10;

FIG. 12 is a front view of the gun stock of FIG. 10;

FIG. 13 is a rear view of the gun stock of FIG. 10;

FIG. 14 is left side view of the gun stock of FIG. 10;

FIG. 15 is a right side view of the gun stock of FIG. 10;

FIG. 16 is a top view of the gun stock of FIG. 10;

FIG. 17 is a bottom view of the gun stock of FIG. 10;

FIG. 18 is a perspective view of another embodiment of a gun stock in accordance with my new design, the gun stock including a removable accessory ammunition magazine;

FIG. 19 is a front left bottom perspective view of the gun stock of FIG. 18;

FIG. 20 is a front view of the gun stock of FIG. 18;

FIG. 21 is a rear view of the gun stock of FIG. 18;

FIG. 22 is a left side view of the gun stock of FIG. 18;

FIG. 23 is a right side view of the gun stock of FIG. 18;

FIG. 24 is a top view of the gun stock of FIG. 18; and,

FIG. 25 is a bottom view of the gun stock of FIG. 18.

The broken lines immediately adjacent the shaded areas represent the bounds of the claimed design while all other broken lines are directed to environment and are for illustrative purposes only; the broken lines form no part of the claimed design.

1 Claim, 19 Drawing Sheets
